(57) **CLAIM**

The ornamental design for a bidet, as shown and described.

DESCRIPTION

FIG. 1 is a top-front perspective view of a bidet showing the new design;

FIG. 2 is a top-rear perspective view thereof;

FIG. 3 is a top elevational view thereof;

FIG. 4 is a left-side elevational view thereof;

FIG. 5 is a right-side elevational view thereof;

FIG. 6 is a rear elevational view thereof;

FIG. 7 is a front elevational view thereof;

FIG. 8 is an enlarged partial view of FIG. 3;

FIG. 9 is a view of FIG. 8 in an operational state;

FIG. 10 is a view of FIG. 8 in an operational state;

FIG. 11 is a view of FIG. 8 in an operational state;

FIG. 12 is a view of FIG. 8 in an operational state;

FIG. 13 is a view of FIG. 8 in an operational state;

FIG. 14 is an enlarged partial view of FIG. 1; and,

FIG. 15 is an enlarged partial view of FIG. 2.

The broken lines in the figures depict environmental subject matter and form no part of the claimed design.
